UNITED STATES PATENT OFFICE.

FRANK IBERT, OF BROOKLYN, NEW YORK.

BEER-COOLER.

SPECIFICATION forming part of Letters Patent No. 714,703, dated December 2, 1902.

Application filed January 20, 1902. Serial No. 90,388. (No model.)

To all whom it may concern:

Be it known that I, FRANK IBERT, a citizen of the United States, and a resident of Brooklyn, county of Kings, and State of New York, 5 have invented certain new and useful Improvements in Beer-Coolers, of which the following is a specification.

This invention relates to a beer-cooler which thoroughly utilizes the temperature of the 10 cooling medium and effects a rapid and cleanly cooling of the beer.

In the accompanying drawings, Figure 1 is a vertical longitudinal section of my improved beer-cooler; Fig. 2, a cross-section on line 2, 15 Fig. 1; Fig. 3, a plan of partition *j* in cylinder *A*, and Fig. 4 a plan of partition *j* in cylinder *A'*.

The cooler is composed of two cylindrical shells *A* *A'* of like construction, each consisting of an upper section *a* and a lower section *a'*. The sections *a* *a'* are flanged at their ends and are here connected by hinged bolts *a*². Through each shell *A* *A'* extend a series of upright beer-cooling tubes *b*, set into an upper perforated head *b'* and a lower perforated head *b*². Above the head *b'* there is bolted to section *a* a removable bulged cover *c*, having vent *c'*, and below the head *b*² is bolted to the section *a'* a removable bulged bottom *d*. In 30 this way there is formed an upper chamber *a*³ and a lower chamber *a*⁴, that communicate with the pipes *b*. The cover *c* of the first cooler is connected to the bottom *d* of the second cooler by a pipe *e*, having trap *e'*. The 35 beer enters at bottom *d* of the first cooler through pipe *f*, having trap *f'*, then passes through its chamber *a*⁴, pipes *b*, and chamber *a*³ into pipe *e*, and thence into chamber *a*⁴, pipes *b*, and chamber *a*³ of the second cooler, 40 to be discharged through pipe *c*².

To clean the chambers and pipes, the sections *a* *a'* may be unbolted and the cover *c* may be removed and water circulated, so that any sediments are washed out through the 45 traps.

Between the heads *b'* *b*² each of the cylinders *A* *A'* constitutes a cooling-chamber for the circulation of cold water and brine, respectively. This chamber is divided within 50 each shell into an upper and a lower compartment by means of a partition *g*, perforated to snugly embrace the pipes *b* and project-

ing between the contiguous flanges of the sections *a* *a'*. The cooling medium enters the compartment of each upper section *a* through a pipe *h* and is discharged therefrom by a pipe *i*. Between the pipes *h* and *i* there is arranged within the compartment a diaphragm *j*, provided with an opening *j'* diametrically opposite the inlet and discharge pipes *h* *i*, so that the liquid must describe a sinuous course in flowing from the former to the latter, and must thus effectively give off its temperature. The perforation *j'* is of such a size as to surround a number of the pipes *b*, Fig. 2, which 65 pass freely through the same to provide for an ample circulation of the cooling medium. The lower compartments contained within the sections *a'* are in like manner provided with inlet-pipes *k*, exit-pipes *l*, and with an intervening diaphragm *m*, perforated at *m'*, diametrically opposite such pipes. It will thus be seen that the beer in flowing through the pipes *b* is subjected successively to the action of four sinuous streams of cooling liquids, which will reduce its temperature in a rapid manner. Besides, my cooler is so constructed that it may be readily taken apart and all its parts may be thoroughly inspected and cleaned.

80 What I claim is—

1. A beer-cooler composed of a cylinder, a series of pipes extending therethrough, a partition for dividing each cylinder into separate compartments, an inlet and outlet for each 85 compartment, and an intervening diaphragm, perforated out of alignment with said inlet and outlet, substantially as specified.

2. A beer-cooler composed of a cylinder having an upper and a lower section, a partition intermediate said sections to divide the cylinder into two compartments, a series of pipes extending through the cylinder, an inlet and outlet for each compartment, and an intervening diaphragm, perforated out of alignment with said inlet and outlet, substantially 95 as specified.

Signed by me at New York city, county and State of New York, this 11th day of January, 1902.

FRANK IBERT.
